United States Patent Office

Des. 179,317
Patented Nov. 27, 1956

179,317

DOOR KNOCKER

Ted C. Ringman, Mariemont, Ohio

Application April 22, 1955, Serial No. 35,634

Term of patent 7 years

(Cl. D10—7)

Fig. 1

Fig. 2

Figure 1 is a perspective view of a door knocker showing my new design.

Figure 2 is a front elevational view thereof.

I claim:

The ornamental design for a door knocker, substantially as shown.
